Application May 31, 1952, Serial No. 19,972

Term of patent 14 years

(Cl. D48—31)

To all whom it may concern:

Be it known that we, Thayer B. Farrington, Robert K. Farrington, Fred K. Ikeda, and Robert P. Mercer, citizens of the United States, residing at Cleveland Heights, Shaker Heights, Cleveland and Cleveland, respectively, county of Cuyahoga, State of Ohio, have invented a new, original, and ornamental Design for a Lighting Fixture, of which the following is a specification, reference being had to the accompanying drawings, forming a part thereof.

In the drawings,

Fig. 1 is a side elevational view of a lighting fixture showing our new design; while

Fig. 2 is a top plan view of the lighting fixture of Fig. 1.

The dominant features of our design are shown in solid lines.

We claim:

The ornamental design for a lighting fixture, as shown and described.

THAYER B. FARRINGTON.
ROBERT K. FARRINGTON.
FRED K. IKEDA.
ROBERT P. MERCER.
